UNITED STATES PATENT OFFICE.

FRED E. WILCOX, OF SYRACUSE, NEW YORK.

DESIGN FOR A BEDSTEAD.

SPECIFICATION forming part of Design No. 21,856, dated September 13, 1892.

Application filed July 18, 1892. Serial No. 440,406. Term of patent 7 years.

To all whom it may concern:

Be it known that I, FRED E. WILCOX, of Syracuse, in the county of Onondaga, in the State of New York, have invented a new and ornamental Design for Bedsteads, of which the following, taken in connection with the accompanying drawing, is a full, clear, and exact description.

My invention is a design for bedsteads, as will be hereinafter more fully pointed out.

In the annexed drawing is represented a perspective view of a bedstead provided with my new design.

My design consists in its characteristic features of the novel head and foot pieces, the upper part of which represents the form of a bicycle-wheel divided in half and so arranged

that the rims of the half-wheels terminate in or are connected with the upper ends of the posts. Within the rims are the hubs of the wheels, and radiating from the hubs are spokes running to the rims, thus giving the appearance of half of a wheel as the upper terminus of each end of the bed.

Having described my invention, what I claim as new is—

The design for a bedstead herein shown and described.

In testimony whereof I have hereunto set my hand this 23d day of June, 1892.

FRED E. WILCOX.

Witnesses:

FREDERICK H. GIBBS,
R. J. SCHUHMANN.
